US0D1051065S

(12) **United States Design Patent** (10) **Patent No.:** **US D1,051,065 S**
(45) **Date of Patent:** **** Nov. 12, 2024**

(54) **ELECTRICAL PORT**

(71) Applicant: **THE NOCO COMPANY**, Glenwillow, OH (US)

(72) Inventors: **Jonathan Lewis Nook**, Gates Mills, OH (US); **William Knight Nook, Sr.**, Shaker Heights, OH (US); **James Richard Stanfield**, Glendale, AZ (US); **Derek Michael Underhill**, Tempe, AZ (US)

(73) Assignee: **The Noco Company**, Glenwillow, OH (US)

(**) Term: **15 Years**

(21) Appl. No.: **29/813,962**

(22) Filed: **Nov. 2, 2021**

Related U.S. Application Data

(63) Continuation of application No. 29/756,091, filed on Oct. 26, 2020, now Pat. No. Des. 936,592, which is a continuation of application No. 29/682,404, filed on Mar. 5, 2019, now Pat. No. Des. 903,602.

(57) **CLAIM**

The ornamental design for an electrical port, as shown and described.

DESCRIPTION

FIG. 1 is a perspective view of an electrical port, with the cover in an open configuration;

FIG. 2 is a front elevational view thereof;

FIG. 3 is a rear elevational view thereof;

FIG. 4 is a right side elevational plan view thereof;

FIG. 5 is a left side elevational plan view thereof;

FIG. 6 is a top plan view thereof;

FIG. 7 is a bottom plan view thereof; and,

FIG. 8 is another perspective view, with the cover in a closed configuration.

The broken lines illustrate portions of the electrical port and environmental subject matter that form no part of the claimed design.

1 Claim, 8 Drawing Sheets
